HOUSING FOR A THERMOSTATIC CONTROL OR SIMILAR ARTICLE

James FitzGerald Bowlby, Butler, N.J., assignor to
American Thermostat Corporation, South Cairo, N.Y.,
a corporation of New York

Filed Nov. 23, 1959, Ser. No. 58,430

Term of patent 14 years

(Cl. D26—13)

FIG. 1

FIG. 2

Fig. 1 is a rear perspective view of a housing for a thermostatic control or similar article, showing my new design; and

Fig. 2 is a front perspective view thereof.

The broken line showing of a representative control knob in Fig. 2 is for illustrative purposes only.

The ornamental design for a housing for a thermostatic control or similar article, as shown and described.

I claim:
